REMOTE CONTROL SYSTEM

Duncan J. Stewart, Rockford, Ill., assignor to
Howard D. Colman, Rockford, Ill.

Application December 15, 1933, Serial No. 702,434

10 Claims. (Cl. 177—353)

The invention pertains to a system of remote control and involves the transmission of a signal from a remote point, for example, from a motor vehicle to control a power driven mechanism such as an electrically driven door operator by means responsive to the transmitted signal.

One object of my invention is to provide a control system of the character indicated, which is simple in construction, so as to be capable of being supplied at a relatively low cost, and which is reliable in operation.

Another object is to provide a control system of the aforesaid character, including a sensitive detector element responsive to signals transmitted from a remote point and operable to perform the desired controlling function only upon receipt of a signal combination of a preconcerted character, thereby avoiding unintended or accidental operation.

The accompanying drawings illustrate the invention in a preferred embodiment, applied to the control of a garage door operator and utilizing radiant energy signals of a preconcerted character transmitted from a motor vehicle. It should be understood, however, that the invention is susceptible of wide application and in its broader aspects, is not limited to the use of radio signals. In the drawings:

Figure 1 is a perspective view illustrating schematically a power driven garage door operator adapted to be controlled by means of a signal transmitted from a motor vehicle shown in approaching relation to a garage.

Fig. 2 illustrates a time chart showing the sequential operation of various parts of the control mechanism with respect to a transmitted signal of a preconcerted character.

Fig. 3 is a schematic view partially in perspective showing the transmitting and receiving mechanisms with an electrically driven door operator connected with the receiver, the door operator being shown schematically.

In one aspect, my invention is an improvement upon the selective signalling apparatus of the patent to Howard D. Colman, No. 1,760,479, dated May 27, 1930. Generally stated, the improvement resides in the simplification of the transmitting and signal responsive control mechanisms. Thus, according to my invention, the transmitter may be of a simplified character, involving merely the use of a manually operable switch in place of a mechanically timed sending mechanism, and the control mechanism operating in response to the received signal involves a simple motor driven device whose operation is initiated upon the receipt

of the initial impulse of the transmitted signal, but depends, for the proper completion of the cycle and the performance of the intended operation, upon the receipt of a complete signal of preconcerted character.

Referring now to the drawings, the motor vehicle (Fig. 1) is equipped with a signal transmitting mechanism including a sending antenna 4 which may be mounted beneath the body of the vehicle in the manner disclosed in my prior Patent No. 1,792,193, dated February 10, 1931. In the driveway leading to the garage is a receiving antenna 5 leading to a signal responsive control mechanism within the garage and governing an electrically driven door operator shown diagrammatically at 6.

As shown at the left of Fig. 3, the sending antenna 4 is connected with an induction coil 7, which in turn is in circuit with a car battery 8 and a manually operable switch 9 on the instrument panel of the vehicle, the general arrangement being the same as shown in the said Colman Patent No. 1,760,479, except for the use of the manually operable switch 9 in place of a mechanically operated switch. Accordingly, in the present instance, the character of the signal transmitted is determined by the manner in which the switch 9 is operated by the driver of the vehicle. It will be understood however, that instead of manual operation a simple mechanical operator under manual control may be employed.

The power driven door operator, which may be of the type disclosed in the said Colman patent, includes a reversible electric motor 10 (shown at the right in Fig. 3) for actuating the door or doors as the case may be. Electric power is supplied to this motor under the control of a main switch 11 interposed in one side 12 of a power line, of which 13 designates the other side.

The receiver for the transmitted signals forms per se no part of this invention, being substantially the same as in said Colman patent. As shown, it comprises in addition to the receiving antenna 5 a radio frequency coil 14 grounded at 15. 16 designates generally a vacuum detector tube of the three element type, comprising a grid 17, a plate 18, and a filament 19.

The filament is adapted to be heated continually from an alternating current line through a transformer 20 stepping down the voltage to approximately 6 volts. The alternating current as applied at 110 volts to the plate or control circuit 21 is rectified by the detector tube and used to energize an electromagnetic control device. The change in the output power upon the re-

ception of a signal is sufficient to operate such a control device. As shown, the plate circuit 21 has interposed therein a magnet 22 having an armature 23 operating in response to the received signal.

24 is a grid condenser and 25 a variable condenser. The wave trains constituting the impulses of the transmitted signal, affect the grid in the well known manner, producing negative charges thereon which cause a decrease in the current in the plate circuit. A by-pass condenser 26 around the relay or magnet 22 serves to prevent chattering of the armature. The filament transformer 20 is connected by conductors 27 and 28 with the opposite sides 12 and 13 of the alternating current line.

The armature 23 of the relay is pivotally mounted at 31, and is urged by a spring 32 in a direction away from the magnet pole. Normally, however, the armature is attracted by the magnet. Thus, when no signals are being received, the plate current flowing through the relay coil 22 energizes the relay. On the other hand, when a signal is being received, a reduction in the plate current occurs, de-energizing the relay and permitting movement of the armature 23 by the spring 32.

In carrying out my invention, the operation of the relay under the control of the received signal is utilized first, to initiate the operation of a control device governing the actuation of the main motor switch 11 of the door operator, and then to insure continued operation of the control device through a complete cycle. To effect proper operation of the relay to produce this result, the signal must be composed of units of different kinds, viz., impulse and space units, and these units must also occur in proper timed relation in the control cycle.

40 The control device in the present instance comprises a shaft 33 having a series of cams thereon. This shaft is driven through the medium of a suitable gear train 34 by an electric motor having a rotary drive shaft. Preferably, I employ 45 a small shading ring induction motor 35 having an energizing winding 36. Thus the driving means is of such character as to be operative upon continuous energization of the motor from a local source of current as distinguished from 50 an interrupted energization as in the case of ordinary stepping magnets directly responsive to a succession of transmitted impulses.

55 Energization of the motor 35 to start the cam shaft through an operating cycle is effected by the relay 22 under the control of the incoming signal. As herein shown, the cycle is initiated by the armature 23 and its spring 32 as an incident to the reduction of the current in the plate circuit following the receipt of an initial impulse unit. In such movement, the armature 23 closes 60 a switch 37 the movable contact of which is carried by the pivoted armature support and is electrically connected by conductors 29 and 30 with a conductor 21^a forming part of the control circuit 21 and connected to the line conductor 27. The stationary contact of this switch 37 is formed 65 by an adjustable screw 38.

Said switch 37, hereinafter referred to as the primary relay switch, acts jointly with a switch 39 controlled by a cam 40 on the cam shaft 33 to energize the motor 35 and initiate the cycle.

70 As shown, the cam 40 has a single lobe acting in the normal or rest position of the cam shaft to maintain the switch 39 closed. Of this switch, the stationary contact 41 is connected by a con-

ductor 42 with the stationary contact 38 of the primary relay switch 37, and the movable contact 43 of the switch 39 is electrically connected to a conductor bar 44 from which a conductor 45 leads to the motor energizing winding 36. The 5 opposite end of the winding 36 is connected by a conductor 46 to the line conductor 28. It will be seen that the switch 39 constitutes a starting switch for initiating the operation of the cam shaft 33 under the control of the primary relay 10 switch 37 operating in response to an initial impulse unit of the received signal.

The cycle of operation of the present motor driven control device may be considered as being divided into two parts or movements, one initiated by the joint action of the switches 37 and 39, and a second or final movement occurring as a continuation of the first movement provided the incoming signal is of a predetermined character. Accordingly, I provide means operating to cause 20 the cam shaft 33 to revolve, when once started, through one-half revolution, and then to interrupt such movement unless the interrupting means is rendered ineffective by the receipt of a signal unit of a certain kind. In the latter 25 event, the operation of the cam shaft is continued for the remainder of the cycle.

The means for insuring at least the first portion of the movement of the cam shaft comprises in the present instance, a cam 47 having 30 two diametrically opposed notches 48 and controlling the operation of a switch 49 independently of the relay 22. The movable contact of this switch 49 is connected to the bar 44 electrically connected by the conductor 45 with one end of 35 the motor winding 36, and the stationary contact of said switch 49 is connected by a conductor 50 and the conductors 30 and 21^a to the line conductor 27. In the initial or rest position of the cam shaft, the switch 49 is open, but after 40 the cam shaft is started by the joint action of the switches 37 and 39, the switch 49 is closed by the cam 47, so that the shaft 33 will revolve at least through one-half revolution or until the opposite notch 48 of the cam 47 permits the running switch 49 to open.

The ability of the switch 49 to interrupt the rotation of the cam shaft after the first movement thereof is dependent upon a variation in the transmitted signal and, in the present instance, upon the occurrence of a space unit controlling the operation of the relay 22 in advance of the opening of the switch 49. Such space unit is rendered effective through the conjoint operation of the relay and a third switch controlled by 55 the cam shaft to continue the movement thereof through a complete cycle. Thus, I provide a secondary relay switch 52 arranged to be closed by the relay armature 23 in response to the receipt of a space signal unit and an auxiliary running switch 53 in series with the switch 52 and arranged for actuation by a cam 54 on the cam shaft.

The movable contact of the auxiliary running switch 53 is electrically connected with the motor 65 as in the case of the switches 49 and 39, and the stationary contact thereof is connected by a conductor 53^a with the stationary contact of the secondary relay switch 52, mounted on a suitable bracket 55. The relay armature carries the movable contact of the latter switch.

By the arrangement thus set forth when a space unit occurs in the received signal in advance of the opening of the auxiliary running switch 53, the relay coil 22 is energized so as to attract the 75

armature and close the relay switch 52. If, therefore, the auxiliary running switch 53 has at this time been closed, the circuit to the motor is completed. The cam 54 is, of course, designed to hold the switch 53 closed long enough to maintain the motor energized until the control of the motor is restored to the main running switch 49, it being observed that the switch 49 is opened only momentarily at the end of one-half revolution of the cam shaft.

The initiation of a door operating cycle is under the control of the timing device during the latter portion of its complete operating cycle, and such operation of the door operator is also made dependent upon the character of the received signal. To this end, I provide a switch 51 arranged to be closed by a cam 58 on the shaft 33 near the end of the complete control cycle. This switch 51 operates in conjunction with the primary relay 37 to control the energization of a magnet 59 arranged to close the main motor switch 11 in any suitable way as, for example, that shown in the said Colman patent. Said magnet 59 may be energized from the door operator circuit which is connected with the main supply line 13 through the medium of the reversing switch of the operator 6 and the normally closed field switch of the motor 10, the other end of the magnet coil being connected by a conductor 60 with the movable contact of the switch 51. The stationary contact of this latter switch is connected by a conductor 61 to the stationary contact 38 of the primary relay switch 37, so that when the latter switch is closed, the above described circuit for relay 59 is extended by way of conductors 29, 30, 21^a and 27 to conductor 12 of the power line. Accordingly, operation of the main motor control switch 11 is dependent upon the simultaneous closure of the primary relay switch 37 and the cam actuated switch 51, the former closing in response to the receipt of a signal unit in the form of an impulse rather than a space unit.

From the foregoing, it will be apparent that the control cycle as well as the initiation of a door operating cycle is under the control of a signal composed of an initiating impulse unit, a continuing space unit, and a final impulse unit. Therefore, the operator of the motor vehicle must in order to effect the operation of the door operator, actuate the transmitter switch 9, first to close the same, then to open the same, and finally to close the switch, the opening and final closing operations of the switch 9 to be performed in timed relation to the operation of the main running switch 49 by its cam 47 and to the operation of the door control switch 51 by its cam 58, as will be hereinafter more particularly set forth, in connection with the time chart (Fig. 2).

In the preferred embodiment, a special mechanically actuated grid discharge device is employed in connection with the radio receiver circuit for the purpose of conditioning the detector tube and the relay controlled thereby, so as to insure proper operation of the relay armature 23 in response to the received signal units. This discharge device comprises a switch 62 arranged for actuation by a cam 63 on the shaft 33 and having a stationary contact connected by conductors 63^a and 63^b with the grounded side of the tube filament 19, and a movable contact connected by conductors 65 and 65^a with the grid. The cam 63 has two diametrically opposed lobes operable to close the switch 62 and thereby permit discharge of the grid first, after the receipt

of the first signal unit, and again after the receipt of the third signal unit. In the first instance, such discharge of the grid insures prompt restoration of the plate current in the relay control circuit, so that upon the reception of the space signal unit the secondary relay switch 52 will be closed for operation in conjunction with the auxiliary running switch 53 in continuing the control cycle. Also, such initial discharge of the grid insures that the detector tube will be conditioned for the reception of the third or impulse signal unit which, together with the switch 51, controls the main door motor switch 11. The second grid discharge, occurring near the end of the control cycle, operates to condition the tube for the reception of the first impulse unit of the next signal, so that immediately upon the termination of one signal, another signal may, if desired, be transmitted and received.

The use of a mechanically operating grid discharge device is preferred for the reason that it effects a rapid restoration of the detector tube after each impulse unit is received. If desired, however, an ordinary grid leak may be used in addition to such a mechanical device, and I have shown in broken lines in Fig. 3 a grid leak 66 connected in an ordinary way. If such a grid leak is used, the length or duration of the first signal impulse is not important. Thus it is only necessary that the first impulse unit be interrupted so that a space unit will occur and thus permit of closure of the secondary relay switch 52 for cooperation with the auxiliary running switch 53 to complete the cycle, and that a second impulse unit occur to effect a closure of the primary relay switch 37 in proper timed relation to the door control switch 51. Thus, in this instance, a greater latitude is allowed the operator to effect the desired control.

Referring now to the time chart (Fig. 2), the operation will be summarized and the sequence particularly set forth in connection with the preferred embodiment of the invention:

Assuming the control device with its cam shaft 33 to be in its normal rest position as shown in Fig. 3, and that the operator of the motor vehicle has commenced the transmission of a signal by the closure of the transmitting switch 9. As a result of such closure of the switch 9, a first or impulse unit of the signal is picked up by the receiving antenna 5 and causes a reduction in the plate current of the receiver control circuit which permits of the actuation of the armature 23 by its spring 32. The primary relay switch 37 is thus closed, and this switch acting jointly with the closed starting switch 39 initiates a control cycle. In the present instance a complete control cycle is one complete revolution of the cam shaft. Shortly after such initiation of the control cycle, the main running switch 49 is closed by its cam 47 as indicated at *a* in the time chart, and as soon as this switch 49 has been closed, the starting switch 39 is opened as indicated at *b*. Thus, the control device is started through its first half cycle under the control of the first or impulse unit of the signal.

The continuation of the control device through the second portion of its cycle requires the termination of the first or impulse unit of the signal substantially in advance of the opening of the main running switch 49, which occurs at the end of one-half revolution, as indicated at *c*, in the time chart. This is for the reason that the tube must be conditioned for the succeeding space unit controlling the operation of the control de-

vice through the second portion of its cycle by means of the secondary relay switch 52 and the auxiliary running switch 53 closed by the operation of the cam 54 at d. Accordingly, as shown in the time chart, the first signal unit should be terminated well in advance of the closure of the auxiliary running switch 53 at d, as for example at e, corresponding in time to the closing of the grid discharge switch 62 at point f through the operation of a cam 63. In any event the first impulse must be terminated somewhat in advance of the point g, when the grid discharge switch opens, to insure that the latter switch shall be held closed long enough to effect a complete discharge of the grid of the tube 16.

Upon such discharge of the grid the plate current in the control circuit is promptly restored, so that the relay 22 becomes energized to effect closure of the secondary relay switch 52, while the auxiliary running switch 53 is closed at d for cooperation with the switch 52 in continuing the energization of the motor. Consequently, the subsequent opening of the main running switch at c is ineffective to stop the control motor so as to interrupt the cycle at the end of its first movement. The auxiliary running switch 53 remains closed until point h sufficiently subsequent to the closure of the main running switch 49 at point i to insure transfer of control from one switch to the other. On the other hand it will be understood that if an impulse unit should be received at any point subsequent to the point g and in advance of the point i, the secondary relay switch will be prevented from closing and therefore the driving motor will be stopped in an intermediate position.

Assuming that a complete cycle of the control device has been assured, energization of the main motor switch 11 to initiate operation of the door operator, is still dependent upon the proper transmission of an impulse unit constituting the third unit of the signal. The grid or tube having been discharged as above set forth, this third or impulse unit must be received in proper timed relation to the actuation of the door control switch 57 by its cam 58. As shown, such closure of the door control switch 57 occurs at point j as shown in the time chart, and in order that the relay switch 37 will have been closed in advance of the closure of said switch 57, the third signal unit, while indicated on the chart as commencing substantially at k, must be received between the points i and l. If received before point i, it will prevent closure of the secondary relay switch 52; and if received subsequent to point l, the door control switch will have opened. As shown on the chart, the door control switch 57 remains closed for a short time, between points j and l; and the third signal unit is shown as terminating at m, although it may be continued somewhat beyond this point as will presently appear.

To condition the tube for the immediate reception of the first impulse unit of a succeeding signal, should that be desirable, the grid discharge switch 62 is again closed at n and again opened at o just in advance of the termination of the cycle. Similarly, the starting switch 39 is closed at p and the main running switch 49 opened at q preparatory for the next cycle.

From the foregoing it will be apparent that in accordance with the arrangement provided in this exemplary embodiment of the invention, a proper control cycle requires that the operator send first, an impulse unit terminating before point g; second, a space unit between points

g and i; and third an impulse unit between points i and l. Moreover, the third unit must be terminated in advance of the point o to avoid initiation of another control cycle.

It will be observed that by the arrangement thus set forth, the operator of the vehicle may by a proper timing of the operation of the manual transmitting switch 9, initiate from a remote point the operation of the power driven door operator, it merely being necessary that the operator cause the switch 9 to be open for the transmission of a space signal unit in proper timed relation to the mechanical operation of the main and auxiliary running switches. Exact timing is, however, not necessary, and the operation of the control device at true synchronous speed is also not required. In other words, the method of control employed is sufficiently flexible to permit of slight variation in timing, both in so far as the human element is concerned and also, with regard to the mechanical operation. Should the operator fail to open the switch 9 within the time allotted, the operating cycle will be interrupted at the end of the first movement through the operation of the main running switch 49. In this event, the means for continuing the cycle, namely, the auxiliary running switch 53 and the secondary relay switch 52, will be rendered ineffective because of the failure of the relay 22 to close the switch 52. Similarly, in the event of initiation of the cycle by a single electric impulse, such as may occur in a thunder storm, the cycle will be interrupted at the end of the first movement. When such interruption occurs, completion of the cycle is retarded until the charge leaks off the grid sufficiently to permit the relay 22 to become energized and thereby effect a closure of the secondary control switch 52. In this connection, it will be seen that the cam 54 operating the auxiliary running switch 53 is so constructed as to hold the switch 53 closed when the control device is in an intermediate position at the end of the first movement.

Also, it will be observed, that even though a first or impulse unit be terminated properly so as to effect a completion of the control cycle, initiation of the door operating cycle is still dependent upon the transmission of an impulse to constitute the third unit of the signal; and that this impulse must be transmitted so as to occur in timed relation to the closure of the door control switch 57 by the cam 58. Therefore, the transmission of a short impulse constituting the first unit of the signal followed by a space unit continued throughout the remainder of the cycle, would be ineffective to initiate a door operation.

In the event that a grid leak 66 is used in addition to the mechanical grid discharge, the first impulse unit of the signal may be continued, as for example to point r, reference being made to the time chart in which this modified signal is shown in broken lines. Thereafter, the occurrence of a short space unit in the signal will permit the continuation of the operating cycle through a closure of the secondary control switch 52. Finally, transmission of a third unit in the form of an impulse occurring while the door control switch 57 is closed, will initiate the operation of the door motor. It will be seen, however, that greater care is necessary to be exercised on the part of the operator where a mechanical grid discharge is used, and therefore, it is possible with this latter construction to ob-

tain a higher degree of secrecy so as to lessen the possibility of unintended or accidental operation.

I claim as my invention:

5. 1. A control mechanism having a signal responsive receiver, a part to be operated, a primary control means differentially operable in response to a received signal having units of different kinds, and a cyclically operable secondary control means cooperating with the primary control means only upon the receipt of a preconcerted signal combination to initiate the operation of said part, said secondary control means including an electric motor having a control 15 circuit, a plurality of switches actuated by said motor and cooperating with said primary control means at different points in the operating cycle of the secondary control means to maintain said control circuit closed during a predetermined operating cycle, and an additional switch actuated by said motor and cooperating with said primary control means at a point in said operating cycle subsequent to said first mentioned points to initiate the operation of said 25 part.

2. A remote control system comprising a signal responsive receiver, a part to be operated, a control means responsive to different kinds of signal units comprising a received signal combination, a motor driven control means cooperating with the signal responsive control means upon the receipt of a predetermined signal combination to initiate the operation of said part, said motor driven control means including an electric motor energized first in response to one kind of signal unit to initiate a predetermined operating cycle and subsequently in response to a different kind of signal unit to complete said operating cycle, and means actuated at a predetermined point in the cycle subsequent to the receipt of said different signal unit to cooperate with said signal responsive means in initiating the operation of said part.

3. A remote control system having in combination with a part to be controlled, means for transmitting a signal composed of impulse and space units, a control device to be operated through a predetermined cycle, driving means for said device including a rotary electric motor, and means responsive to a transmitted signal of a preconcerted character adapted to cooperate with said control device to control the energization of said motor, said signal responsive means being operative during an intermediate portion of the cycle 55 only under the control of a space unit to maintain said motor energized, and said control device having means cooperating with said signal responsive means in response to a signal unit of a predetermined character occurring subsequent to the movement of said device past said predetermined point to govern operation of said part to be controlled.

4. A remote control system having in combination with a part to be controlled, means for transmitting a signal combination composed of units of different kinds, a control device to be operated through a predetermined cycle, driving means for said device including a rotary electric motor, and means responsive to a transmitted signal of a 60 preconcerted character and adapted to cooperate with said control device to effect movement of said device through said cycle, said signal responsive means being operative under the control of a signal unit of a predetermined character only to maintain said motor energized at

an intermediate point in the cycle, and said control device and signal responsive means being further operative under the control of a signal unit of a predetermined character occurring subsequently to the movement of said device past 5 said predetermined point to govern the operation of said part to be controlled.

5. A remote control system for effecting a control operation in response to a particular signal, said system having, in combination, means for 10 transmitting a signal composed of units of different kinds occurring in succession, a control device to be operated through a predetermined cycle, driving means for said device including an electric motor, and means responsive to a transmitted signal of a preconcerted character adapted to cooperate with said control device to effect movement thereof through said cycle, said control device including two motor control switches and a third switch, and said signal responsive means being adapted to cooperate with said two motor control switches at different times in response to signal units of different kinds to govern the energization of said motor, and to cooperate with said third switch in response to 20 a signal unit received subsequent to the signal units governing the energization of the motor to effect a control operation.

6. A remote control system having, in combination with a part to be controlled, means for transmitting a signal composed of units of different kinds, a control device to be operated through a predetermined cycle, driving means for said device including a rotary electric motor, and means responsive to one unit of a transmitted signal of 30 a preconcerted character adapted to cooperate with said control device to initiate movement thereof through a part of said cycle and responsive to another unit of said signal to initiate movement of the device through the remainder 35 of said cycle, said control device including means operative in conjunction with said signal responsive means in the latter part of the cycle to govern the operation of said part to be controlled. 45

7. A remote control system for effecting the operation of a motor driven operator, said system having a motor driven control means, including an electric motor and a control element to be driven thereby through a predetermined 50 cycle, means for initiating the energization of said motor from a normal rest position including a signal responsive device responsive to one kind of signal unit, other means operable by said control element in the initial portion of its movement to continue the energization of said motor through a predetermined distance and then to interrupt such energization, means including a second signal responsive device responsive to a different kind of signal unit to render the last 60 mentioned means ineffective to interrupt the energization of said motor, and means actuated by said control element in the latter part of its cycle operative in cooperation with said first signal responsive device for initiating the operation of 65 said power driven operator.

8. A remote control system having, in combination, a control device to be operated through a predetermined cycle, means responsive to a signal composed of impulse and space units including a control circuit having an electromagnet therein and a detector tube having a grid tending to retain the character of an impulse unit of the received signal, said signal responsive means being arranged to cooperate with said control de- 75

- vice in response to signal units of different kinds to effect movement of the device through said cycle, and means operative after the receipt of an impulse unit to discharge the grid of said tube and to condition the magnet for operation only under the control of a space unit following the impulse unit within a predetermined interval.
9. A remote control system having, in combination, a control device to be operated through a predetermined cycle, means responsive to a signal composed of impulse and space units including a controlling circuit having an electromagnet therein and a detector tube having a grid tending to retain the character of an impulse unit of the received signal, means for driving said control device including an electric motor, switch means for controlling the energization of said motor during said cycle including a pair of switches controlled by said magnet in response to an impulse unit and a succeeding space unit, respectively, and a pair of switches controlled by said device cooperating successively with said

first mentioned switches and operative respectively to initiate and maintain energization of said motor; and means for discharging the grid of said tube after the receipt of the impulse unit to condition the magnet for operation only under the control of the succeeding space unit received within a predetermined interval after said impulse unit.

10. A remote control system having a control mechanism including an electric motor having a rotary armature, a control device having a fixed driving connection with said armature and adapted to be driven in one direction only from the beginning of one control cycle to the normal starting position of the next control cycle, a part to be operated, and signal responsive means cooperating with said device at different points in said cycle to control energization of said motor and at a point in said cycle subsequent to said first mentioned points for initiating the operation of said part to be controlled.

DUNCAN J. STEWART.
